NAPHTHA FROM FLUID COKING OF RESIDUA

William J. Mattox, Baton Rouge, La., assignor to Esso Research and Engineering Company, a corporation of Delaware

Application May 31, 1951, Serial No. 229,205

4 Claims. (Cl. 260—683)

The present invention pertains to naphtha improvement and more particularly to the catalytic reforming of hydrocarbon fractions boiling within the motor fuel or naphtha boiling range prepared by the fluid coking of residua to convert said hydrocarbon fractions into motor fuels of improved stability and cleanliness and of good anti-knock quality. Specifically this invention involves treatment of the olefinic gasoline fractions produced in the fluid coking of residua in the presence of hydrogen transfer catalysts under hydrogen transfer conditions to effect partial hydrogenation of diolefinic and/or acetylenic compounds of the cracked components.

Numerous processes have been proposed for the conversion or reforming of hydrocarbon fractions boiling within the motor fuel or naphtha range to increase the aromaticity and improve the anti-knock characteristics of said hydrocarbon fractions. Reforming processes employing catalysts, especially hydroforming and aromatizing, are widely used in the petroleum industry to upgrade or improve the anti-knock characteristics of motor fuels. It has also been proposed to subject naphthenic petroleum fractions to hydrogen transfer with normally liquid olefinic hydrocarbons whereby the naphthenic constituents are converted to aromatics and the olefinic hydrocarbons are converted to paraffinic hydrocarbons by the hydrogen removed from the naphthenic constituents.

In view of the increasing demands for greater volumes of motor fuel of improved anti-knock properties, residuum conversion processes and catalytic reforming processes have been the subject of intensive investigation in an effort to find new catalysts or new conditions or techniques for increasing the total amount of motor fuel produced from the petroleum crude oil and for reforming or upgrading of motor fuel or naphtha fractions to increase yields and/or improve the stability, cleanliness and anti-knock characteristics of the motor fuel product.

It is the object of this invention to provide an improved process for preparing motor fuels in high yields, of good stability, cleanliness and anti-knock properties.

It is also the object of this invention to prepare motor fuels in high yields and with good stability and anti-knock properties by a combined process of coking residua in admixture with naphtha by the fluid coking technique and treating the resultant naphtha under hydrogen transfer conditions to effect simultaneous reforming and stabilization.

It is a further object of this invention to prepare motor fuels by a combined process of coking petroleum residua in admixture with naphtha by the fluid coking technique and treating the resultant naphtha under hydrogen transfer conditions to convert diolefinic and/or acetylenic components to monoolefinic and/or aromatic compounds of improved stability and higher anti-knock properties.

These and other objects will appear more clearly from the detailed specification and claims which follow.

In accordance with the present invention the naphtha produced by coking residual stocks on fluidized, catalytically inert solids such as sand, petroleum coke, pumice

2

or the like at temperatures above 1000° F., preferably between 1050 and 1150° F. in the presence of substantial proportions, at least 25% and preferably about 50–75 vol. percent on total hydrocarbon feed of a naphtha boiling within the range of about 120–430° F. are subjected to hydrogen transfer conditions adequate to effect partial hydrogenation of diolefinic and/or acetylenic compounds of the cracked components. By suitable control of the feed stock and cracking or coking conditions it may be possible to provide sufficient naphthenic compounds in the coker reaction products to obviate the necessity of adding an extraneous stream of naphtha to the coker naphtha to facilitate hydrogen transfer. If the coker naphtha is deficient in naphthenic components however, it is advisable to add virgin naphtha containing substantial amounts of naphthenic hydrocarbons. If desired, one or more of the C₂, C₃ and C₄ fractions of coker reaction products may be combined with the coker naphtha and subjected to the hydrogen transfer treatment. The treatment of the coker naphtha is effected at temperatures of about 100–800° F., at pressures of from atmospheric to about 600 lbs. per sq. inch and in contact with catalysts such as nickel sulfide, tungsten sulfide, molybdenum sulfide, preferably on a suitable support or one or more of the chromites of nickel, cobalt, zinc, copper, magnesium, tin or manganese or a chromia type catalyst such as chromium oxide on alumina or zinc aluminate spinel or there may also be used a supported palladium or platinum composite containing about 0.01 to 2.0 wt. per cent of platinum or palladium upon a suitable support such as activated alumina, activated charcoal or the like.

Reference is made to the accompanying drawing illustrating diagrammatically one embodiment of the present invention.

35 In the drawing 10 is a coking vessel similar to conventional dense bed, bottom drawoff fluidized solids contacting vessels and 11 is a transfer line for the introduction of finely divided solids in admixture with fluidizing gas or vapors. The transfer line discharges into an inlet chamber 12 in the bottom of coking vessel 10. The inlet chamber 12 comprises an inverted conical section superposed by a horizontally disposed perforated plate or grid member 13 which serves to distribute the incoming solids and vapors uniformly over the entire cross section of the coking vessel 10. The coking vessel is charged with finely divided, substantially inert solids such as sand, pumice, petroleum coke, clay, etc., having a particle size of about 30–400 mesh which are maintained as a dense, fluidized, turbulent bed 14 having a definite level 15 or interface 40 separating the turbulent bed or dense phase 14 from an upper dilute or disperse phase 16. Linear superficial gas velocities through the coking vessel 10 may be varied between about 0.3 to about 5.0 ft. per second to establish apparent densities of about 20 to 60 lbs. per cu. ft. in dense bed 14 and about 0.001 to 0.1 lb. per cu. ft. in disperse phase 16.

45 A line 17 is provided through which residua for coking is supplied to the coking vessel 10. The line 17 connects to suitable spray nozzles mounted on manifold or header 18 arranged in the upper parts of the coking vessel 10. The distance of travel of droplets of residuum through the disperse phase, i. e., before contact with the main body of fluidized solids or dense bed 14 should be about 5 to 20 feet, preferably about 10 feet. Design of the coking vessel and the fluidizing conditions therein should be such as will permit a residence time of the upflowing vapors in the dense bed 14 of about 3 to 60 seconds and descending time for liquid residuum droplets through the disperse phase 16 of about 0.5 to 10 seconds depending upon the degree of dispersion of the spray and the velocity of upflowing gases. The liquid residuum feed rate

may be about 0.15 to 3.0 wt./hr./wt. (lbs. of residuum per hour per lb. of solid contact material in the coking vessel). The temperature within the dense bed 14 should be maintained at about 1050-1150° F. by circulation of the contact solids as will now be described.

Contact solids from the dense bed 14 pass downwardly around inlet chamber 12 at the bottom of the coking vessel 10 to an outlet pipe 20. Stripping gas such as steam may be introduced at 19 to remove entrained vaporous material from the contact solids passing to the outlet pipe. Part of the contact solids passing into outlet pipe 20 may be withdrawn from the system through valve controlled discharge line 21 in order to maintain contact solids inventory at the desired level. The remainder of the contact solids pass down through conduit 20, preferably countercurrent to a stream of steam or other inert stripping or fluidizing gas supplied through one or more taps 22 which serves to maintain the solid particles in fluidized condition and remove additional vaporizable materials from the contact solids before admixture of said solids with air or combustion gas.

The stripped contact solids are discharged from conduit 20 through control valve 23 into transfer line 24 where they are picked up by a stream of air or combustion gas and conveyed to heater vessel 25. The transfer line 24 discharges the suspension of contact solids in air or combustion gas into inlet chamber 26 arranged adjacent the bottom of heater vessel 25. The inlet chamber 26, similarly to the inlet chamber 12 in coking vessel 10, comprises an inverted conical section superposed by a horizontally disposed perforated plate or grid 27 which serves to distribute the incoming solids and air uniformly over the entire cross section of the heater vessel 25. The linear superficial velocity of the air or combustion gas passing through heater vessel 25, similarly to the gas velocities through coking vessel 19, may be varied between about 0.3 to about 5.0 ft. per second and forms therein a dense, fluidized, turbulent bed 28 of contact solids having a definite level 29 or interface separating the dense bed from a dilute or disperse phase 30 in the upper part of the heater vessel 25. The combustion gases are withdrawn overhead from the heater 25 through a cyclone separator 31 or the like which serves to separate most of the entrained solid particles which may be returned to the dense bed 28 via the dip leg attached to the bottom of separator 31. The combustion gases pass to the atmosphere via stack 32 or, if desired, to heat recovery equipment and thence to the atmosphere or to storage for use as stripping gas or the like.

In the event that petroleum coke is used as the contact solid, the solid material withdrawn from the coking vessel 10 and supplied to heater vessel 25 will be essentially 100% coke. In case a material such as sand is used as the contact material it is advisable to maintain the coke content at a relatively high level, for example about 5 to 20 wt. percent at all times in order to maintain good burning rates and to achieve good utilization of the air supplied to the heater vessel 25. The solids leaving the coking vessel 10 will ordinarily have a coke content that is about 0.5 to about 10 wt. percent higher than that of the solids leaving the heater vessel. This figure depends upon the amount of coke deposited by the particular feed used and the ratio of solids circulation rate to oil feed rate. Fluidized solid contact material carrying about 5 to 100 wt. percent of coke may be withdrawn from the coking vessel for circulation to the heater vessel at a rate of about 1 to 10 times the total oil feed rate to the coking vessel. The suspension of withdrawn contact material in air or combustion gas passes through the transfer line 24 and distributor plate 27 to form a dense fluidized bed 28 in which the desired amount of coke is burned off of the contact particles. As a result of the combustion of the coke, taking place in the transfer line and heater vessel 25, the solid contact materials are heated to temperatures

of about 1150° to 1300° F. Ordinarily the temperature of the dense bed of contact material in heater vessel 25 should be at least about 50° higher than the temperature of the dense fluidized bed 14 in coking vessel 10. About 5 1000-6000 cu. ft. of air per bbl. of total feed to the coking vessel will suffice to burn off all the coke formed and maintain the system in heat balance at the conditions specified.

Fluidized solid contact material at the temperature of the dense bed 28 is withdrawn through the standpipe 33 connected to the bottom of heater vessel 25. The solid contact materials are aerated and/or stripped with steam or inert gas supplied through one or more taps 34 provided on the standpipe 33. The reheated contact solids are discharged from standpipe 33 through control valve 35 into transfer line 11 where they are picked up by a stream of fluidized gas and conveyed to coking vessel 10 at substantially the same rate at which the solid particles were withdrawn therefrom so as to supply the heat required in coking vessel 10 as sensible heat of the reheated contact solids.

The fluidizing gas used to convey the solid contact particles through transfer line 11 may be steam or an inert gas but is preferably a naphtha cut since the naphtha is not only improved or upgraded by the treatment in the coking vessel 10 but more importantly it appears to exert a synergistic effect on the conversion of the residuum in the coking operation to form larger amounts of valuable liquid products. The naphtha feed stock, which may be a virgin naphtha, a catalytically cracked naphtha, a Fischer-Tropsch naphtha or the like having a boiling range of between about 120 and 430° F. is supplied through inlet 37 and may, if desired, be passed through heater coils 38 disposed in the dense bed 28 in order to preheat the same prior to its passage via line 39 into transfer line 11 where it is mixed with the reheated solid contact particles or it may be supplied in liquid form to transfer line 11 by means of inlet line 40. A further possibility is to utilize naphtha, preheated or not as desired, as the fluidizing medium and to supplement its action by the introduction of a second fluidizing medium such as steam through inlet line 40. Upon contacting the reheated contact solids the naphtha is vaporized and/or partially cracked to form a limited amount of normally gaseous hydrocarbons. The feed rate of the naphtha to line 37 is maintained at a rate of about 0.25 to about 4.0 wt./hr./wt. (lbs. of naphtha per hour per lb. of contact solid in the coking vessel).

Vaporous coking products containing small amounts of entrained solid particles pass into the disperse phase 16 in the upper part of coker vessel 10 and pass therethrough countercurrently to descending droplets of residuum feed. In this way the said residuum feed droplets are preheated and pretreated to give off relatively low temperature coking products during their passage through the dilute or disperse phase. Simultaneously the vaporous coking products are quenched to temperatures approximating or somewhat above the temperature of the residuum feed thereby avoiding excessive cracking. At the same time most of the solid particles entrained with the vaporous coking products become caught by the descending liquid droplets and are thereby scrubbed out of the reaction products so that no special solids separation equipment is required.

The vaporous coking products amount to about 90-95 wt. percent on total feed and pass overhead from coking vessel 10 through line 42 at temperatures of about 700-1000° F. into fractionating column 43. About 20-30 wt. percent of product gases based on total feed are taken overhead from fractionator 43 through line 44 for use in accordance with the present invention as will presently be described. In the event that there are excessive amounts of cracked gases available, part of the cracked gases may be withdrawn from the unit and passed to suitable processing or recovery equipment.

Coker cracked naphtha boiling up to about 430° F. amounting to about 50-70 vol. percent based upon total liquid feed is removed from the fractionation tower 43 through line 45 and treated in accordance with the present invention as will be described below. Coker gas oil boiling within the range of about 430-950° F., and amounting to 5 to 15 vol. percent of the total liquid feed is withdrawn from fractionator 43 through line 46 and may be blended with virgin gas oil and passed to a catalytic cracking operation. Coker bottoms boiling above about 950° F. and amounting to about 1-10 vol. percent of the total feed is withdrawn through line 47 and passed to fuel oil storage or blending or, if desired, the bottoms fraction may be recycled to the coking vessel for retreatment therein.

The foregoing operations are essentially the same as set out in application Serial No. 182,036, filed August 29, 1950, by Charles N. Kimberlin et al., now U. S. Patent No. 2,636,844.

It has been found that the lower-boiling hydrocarbons produced in the coking of residua as described above contain diolefins such as butadiene, pentadiene as well as higher-boiling diolefins and while they may be present in various fractions in appreciable quantities the amounts present are not sufficient to justify their separation. Such materials, however, are not desirable components of feeds to operations involving polymerization, alkylation, etc., and the higher-boiling liquid diolefins are notoriously bad gum formers in naphthas or motor fuels. In accordance with this invention the cracked gaseous product and the naphtha cut removed through line 45 are combined and subjected to a treatment to convert the diolefinic and/or acetylenic components to monoolefinic compounds, or what is equivalent thereto, passing a C₂-, C₃-, or C₄ to 430° F. or lower end point naphtha or gasoline fraction over hydrogenation type catalysts which are active for hydrogenation of diolefins to monoolefins but which are relatively inactive for the hydrogenation of monoolefins to paraffins. If the naphtha or gasoline fraction is somewhat deficient in naphthenic hydrocarbons, i. e., contains less than about 5-15 vol. percent of naphthenes it may be desirable to add a virgin or other naphtha stock to supply naphthenes for hydrogen exchange.

To effect the desired after treatment of the naphtha, the naphtha removed through line 45 and the cracked gases taken overhead through line 44 are combined in conduit 48 after the addition, if desired or necessary, of a naphthenic naphtha supplied through line 49. The resultant mixture is then subjected to hydrogen transfer conditions to effect simultaneous reforming and stabilization.

Suitable catalysts that may be used to effect the selective conversion of the diolefinic and acetylenic components to monoolefins include nickel sulfide, tungsten sulfide, molybdenum sulfide or mixtures of these preferably upon a support such as alumina, silica, zirconia, titania, etc. Instead of said sulfides there may be used one or more of the chromites of nickel, cobalt, zinc, copper, magnesium, tin or manganese. Chromia type catalysts such as chromia on alumina or upon zinc aluminate spinel may also be used. Supported palladium or platinum composites containing about 0.01 to 2.0 wt. percent of platinum or palladium upon a suitable support such as silica gel, activated alumina or activated carbon may be used. In this case it is desirable to add small amounts of oxygen-containing materials such as H₂O, CO, etc. which act as mild poisons and inhibit the hydrogenation of mono-olefins to paraffins.

Contact of the naphtha and the olefinic cracked gases with the above catalytic agents may be effected in any desired manner, for example with finely divided catalyst particles in a fluidized solids reactor system of the upflow or bottom drawoff type or in a fixed or moving bed or in a suspensoid type operation. Contact of the naphtha-cracked gas mixture with the catalyst may be effected

70
75

at temperatures of from about 100 to about 800° F. at pressures from atmospheric to about 600 lbs. per sq. inch gauge. The feed rate should be within the range of about 0.1 to about 5.0 v./v./hr.-(liquid volumes of oil per volume of catalyst per hour). The preferred temperature range will be influenced by catalyst type since the above-described catalysts will not always be equivalent. For example, the nickel sulfide preparations require temperatures of about 300-500° F., copper chromite about 400-650° F., and chromia-containing composites about 500-800° F. Platinum or palladium-containing composites can be used at temperatures of from about 100-750° F.

As shown in the drawing, the mixture of naphtha and cracked gases is passed through conduit 48. Catalyst of the above-mentioned classes is discharged from hopper 49 into conduit 48 in the desired amount. The mixture of catalyst and oil is then passed via line 48 through heater coils 50 which may advantageously be arranged in the dense bed 28 within heater vessel 25. The reaction mixture discharged from heater coils 50 may then be passed through cyclone separators or the like to free the hydrocarbon materials of the accompanying catalyst particles. Alternatively a separate treating vessel could be used charged with a fixed bed of catalyst particles and the mixture of naphtha and cracked gases merely passed through suitable preheater coils arranged in the heater vessel 25 or in a separate furnace and thence through the fixed catalyst bed to suitable fractionating equipment.

30 The following example is illustrative of the present invention:

Example

Employing a 2.4% So. La. residuum (11.9° API gravity) a coking operation was carried out in a fluidized bed of 100-200 mesh sand at an average bed temperature of 1080° F., 1.6 w./hr./w., 14 p. s. i. g., and with 40 wt. per cent steam diluent. The coke produced amounted to 10 wt. per cent of the residuum feed and the approximately 90% of gaseous and liquid products was distributed as follows:

C ₂ -Gas, wt. per cent	12.2
Total C ₃ , wt. per cent	6.3
Total C ₄ , vol. per cent	8.6 (15.8% butadiene).
C ₅ -430° F., vol. per cent	24.7 (9.2% conjugated diolefins).
430-700° F., vol. per cent	16.1.
700° F.+bottoms, volume per cent	30.5.

50 The above C₄ cut plus C₅-430° F. gasoline with about 25 vol. per cent of a naphthenic straight-run gasoline fraction is contacted with a 10% copper chromite-silica catalyst at 600° F. and atmospheric pressure to give without substantial volumetric losses a stable motor fuel of 90-92 55 unleaded research octane number and having less than 1% of diolefins. The C₄ cut low is butadiene but high in total unsaturation (91%) is suitable for alkylation, polymerization, etc.

The foregoing description contains a limited number 60 of embodiments of the present invention. It will be understood, however, that numerous variations are possible without departing from the scope of the following claims.

What is claimed is:

1. A method which comprises coking a petroleum 65 residuum stock in a fluidized bed of substantially inert contact material at temperatures of 1000-1200° F. and subjecting a mixture of the reaction products from said coking process boiling below about 430° F., and a naphtha stock rich in naphthenes to treatment in contact with a chromite hydrogenation catalyst effective for the conversion of diolefinic and acetylenic compounds to monoolefins but which is relatively inactive for the hydrogenation of monoolefins to paraffins thereby selectively converting the diolefinic and acetylenic components to monoolefins.

2. A method which comprises coking a petroleum residuum stock in a fluidized bed of substantially inert contact material in the presence of substantial amounts of added naphtha at temperatures of 1000-1200° F. and subjecting a mixture of the reaction products from said coking process boiling below about 430° F., and a naphtha stock rich in naphthenes to treatment in contact with a chromite hydrogenation catalyst effective for the conversion of diolefins and acetylenic compounds to monoolefins but which is relatively inactive for the hydrogenation of monoolefins to paraffins thereby selectively converting the diolefins and acetylenic components to monoolefins.

3. A method which comprises coking a petroleum residuum stock in a fluidized bed of substantially inert contact material at temperatures of 1000-1200° F. and subjecting a mixture of the reaction products from said coking process boiling below about 430° F., and a naphtha stock rich in naphthenes to treatment in contact with a chromite hydrogenation catalyst effective for the conversion of diolefins and acetylenic compounds to monoolefins but which is relatively inactive for the hydrogenation of monoolefins to paraffins, at temperatures of from 100 to 800° F., pressures of from atmospheric to 600 lbs./sq. in. and at feed rates of from 0.1 to 5.0 v./v./hr. thereby selectively converting the diolefins and acetylenic components to monoolefins.

4. A method which comprises coking a petroleum residuum stock in a fluidized bed of substantially inert contact material in the presence of substantial amounts of added naphtha at temperatures of 1000-1200° F. and subjecting a mixture of the reaction products from said coking process boiling below about 430° F., and a naphtha stock rich in naphthenes to treatment in contact with a chromite hydrogenation catalyst effective for the conversion of diolefins and acetylenic compounds to monoolefins but which is relatively inactive for the hydrogenation of monoolefins to paraffins, at temperatures of from 100 to 800° F., pressures of from atmospheric to 600 lbs./sq. in. and at feed rates of from 0.1 to 5.0 v./v./hr. thereby selectively converting the diolefins and acetylenic components to monoolefins.
